UNITED STATES PATENT OFFICE.

WILLARD F. RICHARDS, OF BUFFALO, NEW YORK, ASSIGNOR TO THE GOULD COUPLER COMPANY, OF NEW YORK, N. Y.

CAR-AXLE BOX.

SPECIFICATION forming part of Letters Patent No. 665,268, dated January 1, 1901.

Application filed September 21, 1900. Serial No. 30,708. (No model.)

To all whom it may concern:

Be it known that I, WILLARD F. RICHARDS, a citizen of the United States, and a resident of Buffalo, in the county of Erie, in the State of New York, have invented a new and useful Improvement in Car-Axle Boxes, of which the following is a specification.

This invention relates more particularly to that class of car-axle boxes in which the lid is hinged to the box at its upper end.

The object of my invention is to so construct the box and lid that a reliable dust-proof joint is obtained between these parts, regardless of any looseness or imperfect fitting of the pintle-pin of the lid.

In the accompanying drawings, consisting of two sheets, Figure 1 is a vertical longitudinal section of an axle-box provided with my improvement, showing the lid closed. Fig. 2 is a similar view showing the lid open. Fig. 3 is a front view of the box with the lid closed. Fig. 4 is a similar view with the lid open.

Like letters of reference refer to like parts in the several figures.

25 A is the usual filling-opening of the axle-box, and B the lid hinged to the same by the pintle-pin b, which passes through the usual eyes c, formed at the upper end of the lid and the perforated upright lug d, arranged centrally at the top of the box.

30 E is the lid-spring, arranged on the inner side of the lid and secured at its lower end to the same. In the construction shown in the drawings the pintle-lug d is provided in its under side with an opening f, in which the free upper end of the lid-spring engages when the lid is closed, and the front side of the lug is formed with an eccentric or cam-face f', against which the free end of the 35 spring bears when the lid is opened, so as to hold the lid in any desired position.

The filling-opening A is provided with a raised marginal rim a, which is provided around its four sides with a rabbet or recess a', in which the lid is seated or countersunk when closed. The inner face of the rabbeted rim is beveled, and the edge of the lid is correspondingly beveled, so as to fit closely into

the rim, as shown in Figs. 1 and 3. The upper portion of the flange a², which forms the bottom of the rabbet a', is cut away in line with the lid-spring E, as shown at a³ in Figs. 1 and 4, to form an opening for the passage of the spring; but the portion a⁴ of the beveled rim-face arranged above said opening is unbroken, like the other three sides of said rim, the portion of said rim directly above the opening a³ being formed by the face of the pintle-lug d, which is flush with the upper portion of the rim. By this construction 50 a continuous beveled bearing-face for the beveled edge of the lid is formed around the four sides of the filling-opening, thereby effectually preventing the entrance of dust at the base of the pintle-lug d, as well as at the 55 bottom and sides of the lid. The beveled construction of the lid and the edge of the filling-opening insures a close seating of the lid in the opening, irrespective of any looseness of the pintle-pin due to imperfections 60 in the castings, inasmuch as the contiguous beveled edges of the lid and the filling-opening center the lid and cause the same to fit 65 squarely in the opening.

g is the lifting lip or tongue, arranged at 70 the lower end of the lid. This lip extends below the lower edge of the filling-opening and is raised sufficiently to allow the lid to be closed without the necessity of recessing the adjacent portion of the rim a, forming a 75 dust-proof joint along the lower edge of the lid as well as at its other three sides.

I claim as my invention—

1. The combination with the body of a car-axle box provided at its top with a pintle-lug 80 and having its filling-opening provided with a raised marginal rim having a beveled inner face, said beveled rim extending continuously around the bottom and sides of the filling-opening and across the front side of said pintle-lug, and a hinged lid provided with a 85 beveled edge which fits into said beveled rim, substantially as set forth.

2. The combination with the body of a car-axle box having its filling-opening provided 90 with a raised marginal rim which is provided

with a beveled inner face and which is unbroken along the lower edge of the filling-opening, of a hinged lid having a beveled edge which fits into said rim, and provided at 5 its lower edge with a raised lifting-lip which extends below said filling-opening, substantially as set forth.

Witness my hand this 19th day of September, 1900.

WILLARD F. RICHARDS.
